DESIGN FOR A LENS STRAP

Charles O. Cozzens, Southbridge, Mass., assignor
to American Optical Company, Southbridge,
Mass., a voluntary association of Massachu-
sets

Application December 16, 1933. Serial No. 50,095

Term of patent 14 years

To all whom it may concern:

Be it known that I, CHARLES O. COZZENS, a citizen of the United States of America residing at Southbridge, in the county of Worcester and State of Massachusetts, have invented a new, original, and ornamental Design for a Lens Strap, of which the following is a specification, reference being made to the accompanying drawing forming a part thereof.

The figure is a perspective view of a lens strap showing my new design.

The horn shaped portion of the front ear may or may not be formed on the second or inner ear as

desired, as it cannot be seen from the front when the device is in use on the face of a wearer and therefore is not essential to the design.

It is also apparent that the holes in the strap may be included or omitted as desired, depending upon the type of connecting means used, that is, whether the connecting means is of the screw type extending through the strap or of the welded type which does not extend through the strap.

I claim:

The ornamental design for a lens strap substantially as shown and described.

CHARLES O. COZZENS.
